ALBERT ENNIS HENDERSON, OF TORONTO, ONTARIO, CANADA, ASSIGNEE TO SUPERIOR TUBES AND ACCESSORIES, LIMITED, A CORPORATION OF CANADA.

PUNCTURE-PROOF TUBE FOR PNEUMATIC TIRES.

1,176,552.

Specification of Letters Patent. Patented Mar. 21, 1916.

Application filed August 11, 1913. Serial No. 784,166.

To all whom it may concern:

Be it known that I, ALBERT ENNIS HENDERSON, a subject of the King of Great Britain, and resident of the city of Toronto, 5 county of York, Province of Ontario, in the Dominion of Canada, have invented certain new and useful Improvements in Puncture-Proof Tubes for Pneumatic Tires, and do hereby declare that the following is a full, 10 clear, and exact description of the same, such as will enable others skilled in the art to which it appertains to make and use the same.

I am aware that it is not new to the art to 15 make an inner tube with a thickened tread portion and to produce compression of the thickened portion by turning the tube inside out by either pulling one end outwardly back upon the body of the tube or inwardly 20 within the body of the tube by use of special forceful means; but in so doing the material of the tube is often strained so as to weaken and distort it in places. Besides, through the method of joining together the ends of 25 the tube a less pliable portion of the tread is created at the point of juncture, thus destroying the uniformity of the character of the said tread portion of the tube.

The objects of my invention are, first: to 30 provide an inner tube for pneumatic tires, having a uniformly thickened tread portion, so constructed as to snugly fit the casing when inflated, thus overcoming the tendency to creep; second: to provide for the circumferential compression of the tread portion by reversing the tube without undue strain; 35 third: to provide means for constructing the tube so as to regulate as may be desired the amount of lateral compression of the said 40 thickened tread portion of the tube when completed; and fourth: to guard against the tendency of the valve to tear out owing to the creeping of the tube in the casing.

In the drawings Figure 1 is a sectional 45 view of the tube as it would appear upon the circular form. Fig. 2 shows a sectional view of the tube removed from the form, reversed and joined together, and then inflated. Fig. 5 is an enlarged transverse sectional view 50 of the portion of the tube at the location where the valve is inserted, showing the overlapping flanges and the embedded strengthening fabric. Figs. 3 and 4 show one type of form on which the tube is built

up and vulcanized. Fig. 5 shows a sectional view of a modified type of the circular form for the tube. Fig. 6 is a sectional view of another form which may be used. Fig. 7 is a longitudinal sectional elevation of a portion of the tube showing the position of the fabric in the thickened tread portion as it is built up on the form. Fig. 8 is an enlarged longitudinal sectional view of the portion of the inner wall of the tube where the valve is inserted showing the strengthening fabric.

Like numerals of reference indicate corresponding parts in each figure.

1 is an air tube for pneumatic tires having a thickened tread portion 2 gradually reducing in thickness as it extends laterally from the center of the said tread down the sides of the tube. In Fig. 1, the tube 1 having the thickened tread portion 2 is shown upon the circular form 3 upon which it is built. The material does not completely surround the form transversely but terminates in the reduced portions 4—4', which are adapted to overlap each other when the tube is reversed, as shown in Fig. 2. The fabric 5 and 5' is embedded in the thickened tread portion at a suitable distance from the inner surface 6, and is applied in longitudinal sections leaving a space 6' between the ends of the strips, and in such formation as to permit a certain amount of longitudinal extension. After the first series of strips 5 is applied, additional rubber is laid on and then a second series of strips 5' is applied covering the spaces in the series 5 and extending so as to overlap the ends of the sections of the series 5, additional rubber is then added as may be desired. Fig. 1 shows a sectional view through a part of the tube in which only the series 5 is shown, being opposite the space in the series 5', while in Fig. 2 the double series is shown. This method of construction, more particularly shown in Fig. 7, provides sufficient amount of elasticity to always insure a snug fit of the tube within the casing, thus preventing the tube from creeping in the casing, which is quite impossible when a single strip of fabric extends in a continuous circle throughout the tread longitudinally. The form 3 shown in Fig. 3 being circular in shape permits the building of the thickened tread 2 in one continuous circle and obviates the necessity of

having a transverse joint, so that the tread will be uniform throughout, thus removing a cause of creeping which is found in the ordinary thickened tread. When the proper thickness of tread and wall is obtained, the rubber is rolled and wrapped, and is then vulcanized upon the form to a suitable stage, after which it is easily removed from the form without undue strain owing to the elastic character of the thinner sides of the tube. The tube is then easily reversed laterally or turned inside out as shown in Fig. 2, after which the edges 4-4' may be joined together, the air valve seat being inserted during this operation.

In Fig. 2, the thickened portion 2 of the tread inside the fabric 5-5' will be in compression longitudinally owing to the fact of the inversion of the tube and the restraining influence of the fabric 5 and 5', while the joining together of the overlapping portions 4 and 4' in conjunction with the inflation of the tube produces lateral compression of the thickened tread portion, the amount of said lateral compression being regulated by the ratio of the transverse sectional diameter of the form 3 to the intended diameter of the finished tube.

When building up the tube on the form, a suitable strengthening fabric 7 and 7' is inlaid at the location at which the air valve is to be inserted. This is shown in transverse section in Fig. 2^A, and in longitudinal section in Fig. 8. Owing to the presence of this fabric the ordinary valve cannot be inserted or removed in the usual way at this point, but may be applied in the usual way at any other suitable location. I therefore provide a valve seat 8 having a shank 9 provided with an aperture 10 and holes 11 by means of which the valve seat may be held from turning by a wrench. Said seat may readily be inserted from within the tube when the parts as shown in Fig. 2^A are brought together so that the holes 12 and 12' in the overlapping portions 4-4' are in alinement. The shank 9 extends through the material a suitable distance so as to receive the washer 13 and the nut 14. The shank 9 is interiorly screw-threaded to receive the stem 15 of the ordinary valve which is threaded to engage the shank 9. The rubber washer 16 engaging the end of the valve stem 15 and the shoulder 17 of the valve seat 8 prevents any leakage of air. After the valve has been inserted the remainder of the overlapping portions 4-4' may then be joined together. When the tube is thus completed it is partially inflated and then further vulcanized, it is then ready for use.

Figs. 3, 4, 5 and 6 give details of the forms on which the tube may be molded.

In Fig. 7 the relation of the fabric 5-5' as it is embedded in the thickened tread portion is shown in detail.

It is understood that this method of inserting the fabric may be used in and applied to all thickened treads for inner tubes, whether constructed as described in the specification herein or on any circular or otherwise shaped form where fabric is required for the purpose of compression.

By constructing the tube as above described, I have provided for threefold compression of the thickened tread portion in such degree as to render the same proof against the results of puncture, while the thickened tread being uniform throughout and provided with a certain amount of elasticity, will fit snugly in the casing, and thus overcome the difficulty caused by the creeping of the tube in the casing.

I have thus provided a puncture proof inner tube for pneumatic tires having a uniform tread which can readily be constructed, and from which has been eliminated the weakness inherent to the so-called puncture proof tubes such as have been known to the art, and I construct the same in a manner which has not heretofore been patented or known before my invention thereof.

I do not confine myself to the exact forms or methods of construction shown in the drawings and described in the specification but may vary the same without departing from the spirit of my invention.

I claim:

1. A tube for pneumatic tires having its tread portion held in compression by a series of unconnected terminally overlapping strips of substantially non-elastic flexible material embedded therein adjacent the ultimate tread surface.

2. A tube for pneumatic tires having its tread portion held in compression by a series of unconnected fabric strips embedded therein adjacent to the ultimate tread surface, the adjacent ends of the strips being surrounded by and separated from each other by unrestricted rubber.

3. A tube for pneumatic tires having its tread portion held in compression by a series of unconnected terminally overlapping fabric strips embedded therein adjacent to the ultimate tread surface.

4. A tube for pneumatic tires having its tread portion held in compression by a series of unconnected terminally overlapping fabric strips embedded therein adjacent to the ultimate tread surface and spaced apart radially by intermediate rubber.

5. A tube for pneumatic tires having its tread portion held in compression by terminally concentric series of unconnected fabric elements embedded therein adjacent to the ultimate tread surface.

6. A tube for pneumatic tires having its tread portion held in compression by terminally concentric series of unconnected fabric elements embedded therein adjacent to the

ultimate tread surface, the fabric elements being arranged in staggered relation longitudinally of the tread.

7. A tube for pneumatic tires having its tread portion held in compression by concentric series of terminally concentric and unconnected non-elastic elements embedded therein adjacent to the ultimate tread surface.

8. A tube for pneumatic tires having its tread portion held in compression by a series of terminally concentric and unconnected fabric elements embedded therein adjacent to the ultimate tread surface, the elements of one series occupying a staggered relation with those of the other series.

9. A puncture proof tube for pneumatic tires, built upon a circular form, said tube having a uniformly thickened tread portion circumferential entirety provided with overlapping centrally disposed fabric strips embedded adjacent to the ultimate tread surface, said fabric strips holding the tread portion in compression.

10. In a device of the nature described, in combination, a rubber tube having a tread portion, fabric embedded in the tube adapted to constrict rubber in the tread portion transversely, and rubber interposed between breaks in the fabric and connected thereto, whereby the fabric may be stretched circumferentially beyond its own elasticity while retaining its transverse constricting effect.

11. In a device of the nature described, in combination, a rubber tube having a tread portion, fabric embedded in the tube adapted to constrict rubber in the tread portion transversely, and means comprising elastic material connecting two circumferentially overlapping ends of the fabric, whereby the

fabric may be stretched circumferentially beyond its own elasticity while retaining its transverse constricting effect.

12. In a device of the character described, in combination, a rubber tube having a tread portion, and an annular element embedded in the tube and extending opposite the tread portion comprising a fabric adapted to constrict the rubber in the tread portion transversely and having ends overlapped and yieldingly connected to permit expansion of said element circumferentially without losing its constricting effect transversely.

13. In a device of the nature described, in combination, a tube of elastic material, and a longitudinally disposed flexible stay secured to said tube at the tread portion so as to place the material of said tube under transverse compression when the tube is in an inflated condition, said stay comprising a plurality of strips at different portions longitudinally of the tube.

14. In a device of the nature described, in combination, a tube of elastic material, and a longitudinally disposed flexible stay secured to said tube at the tread portion so as to place the material of said tube under transverse compression when the tube is in an inflated condition, said stay comprising a plurality of strips at different portions longitudinally of the tube, the ends of said strips overlapping.

In testimony whereof I have hereunto affixed my signature in the presence of two witnesses.

ALBERT ENNIS HENDERSON.
